UNITED STATES PATENT OFFICE.

THOMAS E. McCANN, OF PHILADELPHIA, PENNSYLVANIA.

DESIGN FOR A COLLAR.

SPECIFICATION forming part of Design No. 20,872, dated June 30, 1891.

Application filed May 13, 1891. Serial No. 392,632. Term of patent 7 years.

To all whom it may concern:

Be it known that I, THOMAS E. McCANN, a citizen of the United States, residing at Philadelphia, in the county of Philadelphia and State of Pennsylvania, have invented and produced a new and original Design for a Collar, of which the following is a specification, reference being had to the accompanying drawings, forming part thereof.

10 Figure 1 is a front view of a collar, showing my design, and Fig. 2 is a side elevation of the same, these two views being deemed necessary to fully show my design.

15 The leading feature of my design is the semicircular figures in which the ends of the collar terminate.

The collar 10 has a band-like figure 11 at its lower edge, in which are the figures 12, which are made to simulate button-holes, and the ends of the collar terminate in the semi-circular figures 13, which when viewed in side elevation appear to stand out from the body of the collar. 20

I claim—

The design for a collar herein shown and 25 described.

THOMAS E. McCANN.
